United States Patent Office.

ROBERT B. GRIFFIN, JR., OF BALTIMORE, MARYLAND.

Letters Patent No. 71,382, dated November 26, 1867.

IMPROVEMENT IN BUTTON-FASTENERS.

The Schedule referred to in these Letters Patent and making part of the same.

TO ALL WHOM IT MAY CONCERN:

Be it known that I, ROBERT B. GRIFFIN, Jr., of the city and county of Baltimore, in the State of Maryland, have invented a new and useful Device for Fastening Buttons and similar devices to any suitable textile or flexible material; and I do hereby declare the following to be a full and exact description thereof, reference being had to the accompanying drawings, forming part of this specification, in which the several figures illustrate various forms of my invention, and the manner of applying the same.

The nature of my invention consists in the construction of a device for fastening those forms of buttons and other equivalent devices, which are provided with shanks and eyes, to any suitable flexible material or article of wearing-apparel, by the combination of an extended loop, base-plate, or strip, to be placed upon one side of the material, with a central coiled ring to engage with and pass through the eye of the button on the other, said coiled ring being so formed as that the point of the coil may be readily inserted into the material, and the coil be passed entirely through without forming an enlarged aperture therein.

My button-fasteners may be made of wire, or out of small plates of thin metal. In forming them of wire, one end of a wire strip, of the proper length, is sharpened, and coiled with one or two turns into a ring, *c*. The remaining length of the wire strip is then straightened out into a plane tangential to the circumference of the coiled ring, or at right angles to the diameter thereof, and doubled upon itself in said plane into loops *a a*, on each side of the ring, forming the base of the device, the end of the wire being finally bent around the foot of the inner turn of the coil forming the ring, as illustrated in Figure 1 of the accompanying drawings.

Figure 3 illustrates a modification in the form of the base, *A*, of my device. This modification consists in bending the wire forming the base back from the ring instead of with it, as in fig. 1, and in doubling the same into but one loop on one side of the ring, at right angles to its diameter, the straight end of the wire projecting and terminating in said plane beyond the ring on the other side thereof, in the place of the second loop *a'*, of fig. 1.

Figure 8 illustrates another modification, in which the wire is crossed in making the straight loop or loops which form the retaining-base *A* of the device, the wire being turned from instead of with the coiled ring in forming the loop. I contemplate, however, in each case, turning the wire with or from the coiled ring, as may be found convenient.

I propose to employ a thin, flat metallic plate, *A'*, as a substitute for a wire in forming my "fasteners," slitting the same longitudinally to its centre, so as to form a narrow tongue, *x*, therein, as illustrated in Figure 4 of the drawings. This tongue is coiled over (or under) inwardly into a suitable ring, *c'*, which will thus stand at right angles to the base-plate *A*, its end being properly sharpened or pointed so that it shall the more readily enter and penetrate the fabric in securing the "fastener" thereto.

Although the simplest manner of forming the coiled ring *c*, with a suitable retaining-base or plate, *A*, is as I have described, by forming it at right angles to the plane of said base, yet it may be bent over so that its diameter shall coincide with or be parallel to said base, as illustrated by the plan view, Figure 7, of the drawings. The wire used may be either round or flat, or where round wire is used the loops of the base *A*, or end of the wire therein, may be alone flattened, as illustrated in figs. 1, 2, and 3 of the drawings.

In using these my improved button-fasteners, the device is first secured to the cloth or other material by inserting the point of the coiled ring *c* into the same, on the reverse or under side thereof, and turning it until it has passed entirely through the right side, drawing the base-loop or plate *A* into close contact with the material on its under side, as shown in Figure 6 of the drawings, (wherein the cloth through the device is secured as illustrated in section,) so as to hold and retain the ring securely in place. The button or other device is then readily secured to the ring by simply passing or turning its eye on to the coils, as shown in figs. 2 and 6.

The fasteners may be made of any suitable metal. They are adapted for securing all kinds of buttons having shanks and eyes, and may be applied to shoes, gaiters, caps, and garments of all descriptions, although, for the sake of neatness, it may be preferable to work a small hole in the material through which the coiled ring of the fastener shall pass; yet this is not essential.

Having thus fully described my invention, I claim as new, and desire to secure by Letters Patent—

My improved button-fastening device, formed of a coiled ring, arranged to pass through the cloth and the eye of the button, and combined with a retaining-base, substantially in the manner and for the purpose herein set forth.

The foregoing specification of my improved button-fastener signed by me, this 19th day of September, 1867.

ROBERT B. GRIFFIN, JR.
